RADIO BEACON SYSTEM

Forrest S. Mabry, Springfield, Mass., assignor to
Westinghouse Electric & Manufacturing Com-
pany, East Pittsburgh, Pa., a corporation of
Pennsylvania

Application November 12, 1937, Serial No. 174,205

3 Claims. (Cl. 250—11)

This invention relates to radio signalling sys-
tems and more particularly to apparatus for
visually receiving radio beacon signals.

One type of radio beacon system in current
use comprises a pair of beams transmitted from
a common source at an angle to each other, the
one beam being tone modulated with a code
signal such as that which represents the letter
"A" and the other beam being tone modulated
with a code signal such as that which represents
the letter "N". The code letter "A" is represented
by a dot-dash, whereas the code letter "N" is
represented by a dash-dot, these two code sig-
nals being so transmitted in time relationship
to each other that the signals will interlock, and
when received at such points where the signals
are of equal intensity, neither signal will be
heard. What the listener will actually hear will
be the tone modulation. The zone or line of
equal signal intensity under normal conditions,
should follow the bisector of the angle formed by
the two modulated beams. If a plane on which
a receiver may be mounted deviates from this
line, one or the other of the code signals will
predominate on the receiver, thus indicating
the position of the plane to the right or to the
left of the radio beacon.

The beacon signals are, according to present-
day practice, interrupted every few minutes to
render station announcements and sometimes
weather reports. When receiving the signals over
a pair of earphones, one can readily distinguish
the A or the N signals when off course, and no
problem of synchronization occurs since there is
no apparatus to be synchronized.

However, when one relies upon some visual
indicating means to render the signals, the oper-
ation of the indicator comes to a halt at every
station announcement or weather report, and it,
therefore, becomes necessary that the indicator
be in synchronism with the signals when it
again starts up in operation. Often a pilot will
find it essential to switch the visual indicator
out of the circuit in order to listen to some other
conversation or reports, and the same situation
arises regarding synchronizing when the pilot
again switches the indicator back into the circuit.

It is an object of this invention to provide a
simple and satisfactory means for visually indi-
cating the code signals referred to and enable a
pilot to determine, by sight, his position relative
to the guiding beacon.

It is another object of this invention to pro-
vide a visual indicator particularly adapted for

the indication of code signals which will permit
a ready and convenient comparison of the in-
tensities of such signals.

Another object of this invention is the pro-
vision of means for visually indicating a plu-
rality of code signals in such manner that the
relative intensities of the signals may easily be
compared.

A further object of this invention is to provide
an indicator adapted for the visual indication 10
of code signals which shall be very sensitive in
its response to code signals of low intensity.

A further object of the invention resides in
a visual indicator for airplane guiding beacons
which shall automatically remain in synchronism
with the beacon signals.

Additional objects of the invention will be
brought out in the following description of the
same taken in conjunction with the accompany-
ing drawings, wherein:

Figure 1 illustrates schematically a visual in-
dicator embodying the details of the invention;

Figs. 2 and 3 disclose in enlarged detail a
gear train construction which comprises an im-
portant element in the improved indicator;

Fig. 4 is a representation of the signals as
transmitted from a beacon station and illustrates
the interruptions occurring for the station an-
nouncements and the succeeding synchronizing
impulse; and,

Fig. 5 illustrates circuit details involved in the
feature of the invention which effects the auto-
matic synchronization of the indicator.

In accordance with the broad idea of the in-
vention, it comprises, when adapted for the re-
ception of beacon signals, a pair of ionizable gas
columns which are so sensitized, by the appli-
cation of a positive biasing potential, that the
columns will ionize upon the addition to the
biasing voltage of a signal voltage of very low
intensity. Each of the gas columns is so con-
nected in the circuit, which involves suitable
speed control apparatus and a decoding switch,
that the column will respond to one of the signals
only to the exclusion of the other. That is,
one column will respond exclusively to the code
signal representing the letter N, and the other
column will respond exclusively to the code sig-
nal representing the letter A. By supporting 40
these gas columns in a position adjacent to each
other, the relative intensities of the two signals
may be readily determined by a comparison of the
height to which the column of gas ionizes in each
of the columns, the height of the glow produced 45
50

by ionization of gas being a function of the signal intensity.

Referring to Fig. 1, for a more detailed disclosure of the improved visual indicator, it comprises a pair of gas columns 1 and 1', each of which, in actual construction, might comprise glass tubes 2 and 2' filled with an atmosphere of neon gas, these two gas columns being mounted adjacent each other in a suitable support 3.

10 The neon gas in these tubes becomes ionizable upon the application of the proper value of potential to a pair of electrodes 4 and 4' extending inwardly for a short distance of the tube at its lower end. A direct-current biasing potential of 15 a value just sufficient to bring the gas in these tubes to the point of ionization is applied to these electrodes, the electrodes of each tube being connected in parallel across this source of direct-current potential, which might comprise a 20 potentiometer 5 connected across a battery or other convenient source of potential, not shown here. One of the connections from the potentiometer is taken from the variable arm, so that the desired potential may be conveniently obtained. Choke coils 9 and 9' segregate the direct 25 current potential source from the signal potentials which are fed to the electrodes 4 and 4'.

The code signals are applied to the gas columns 30 from the output of a receiving set, the proper application of these signals to the gas columns being determined by apparatus so designed as to decode the signals into the "A's" and "N's," respectively, and to properly apply these signals to their respective ionizable columns. Synchronizing means is provided to assure that the 35 signals will not be distributed as potentials indiscriminately between the two tubes. For example that the "N" signals shall not appear across the tube which is intended to display the "A" 40 signals and vice versa.

The apparatus for accomplishing the proper decoding of the signals and the application thereof to their proper indicating tube comprises a decoding cam or switch 6, the configuration of 45 this cam being such that in a given direction of rotation, the extended portions of its periphery represent the letter "N," whereas the depressed portions represent the letter "A," and it will be noted that the two portions of the cam representing these two signals bear the same interlocked 50 relationship as these signals do as transmitted. A contactor 7 bearing against the periphery of the cam is adapted to be displaced by rotation of the cam between two fixed contacts 8 and 8', each of which is connected to one of the electrodes of the ionizable gas columns. The remaining electrodes of these tubes are connected together, and the resulting parallel connection of these two electrodes is connected to one of the 55 output terminals 10' of the receiver. The other output terminal 10 of the receiver is connected to the cam controlled contact 7 through a blocking condenser 11, which excludes any direct current which may be present in the output circuit.

60 In order to obtain proper application of the signals to their respective indicating tubes, and to assure that the signals as reproduced on the indicator tubes will be in synchronism with the signals as transmitted, the rotational speed of the 65 cam and its initial starting position must bear the proper relationship to the time period of each signal and the initial signal transmitted at the moment the indicator is started up in operation. This is all provided for by the application 70 of a motor 12 the armature of which is geared

75 to the decoding cam through a specially constructed type of gear train. The motor 12 may be of the shunt type, the speed of which may be brought up to approximately the proper value by means of a variable resistance 13 connected in 80 series with its shunt field winding 14. The speed at which this motor is designed to operate is determined by the speed at which the decoding cam should rotate and the gear ratio of the gear train interposed between the motor and the decoding cam. When brought up to the proper speed, it will be maintained at this speed by the tone modulation of the incoming signals applied to a synchronizing field winding 15 with which the 85 motor is provided. This winding is connected across the output of the receiver through a series filter comprising a condenser 16 and a choke coil 17, this filter being designed to pass the tone frequency to the exclusion of the code signals and any other incoming modulations. 90

The gear train referred to constitutes a very important link in enabling proper synchronous operation of the indicator. Referring to Figs. 2 and 3 for a more detailed description of the same, it comprises a driven gear 18, on the shaft of 95 which is mounted the decoding cam, and a driving pinion 19 which is coupled or mounted directly on the armature shaft of the motor. The driven gear 18 is of decidedly greater thickness than that of the pinion 19, the latter being normally held in engagement with the driven gear at a position substantially flush with one of the faces of the driven gear by means of a spring 20 on the motor driving shaft. The larger or driven gear is provided with a cutout 21 in its opposite face and at its periphery, the depth of the cutout being approximately half the thickness of the gear. The driving pinion is adapted to be manually shifted against the action of the spring 20 toward the other face of the gear 18 and substantially flush therewith. When so shifted, the pinion 25 will continue to rotate the driven gear until the cutout portion 21 is reached, at which time the pinion will no longer mesh with the driven gear and the driven gear will come to a halt. 30

Under these conditions, the position of the cam 6 on the shaft of the gear 18 should be the same at all times. This particular position of the cam will depend in its initial set-up upon the signal which is first transmitted after such station indication or after any other interruption 35 in the transmission of the "A" and "N" beacon signals. 40

The actual starting up of the indicator after 45 interruption due to station announcements, etc., will be indicated to the pilot by the beginning of the first code impulse, at which instant the pinion is released by the pilot to reengage the driving gear and start operation of the cam. Thus should the code key at the transmitter be so 50 set up as to transmit the letter "A" immediately after a station announcement, the pilot will wait until he hears the dash and then release the pinion in time to start operation of the cam, which should be so positioned as to apply a voltage corresponding to the dot in the letter "A" to the proper neon tube in synchronism with the dot of the letter "A" as received, and thereafter as long as signals are broadcast, the indicator 55 will be in synchronism with the code switch at 60 the transmitter. 65

In order to make certain that the pilot will receive the starting signal, namely, the dash of the letter "A" should he be off course on the "N" 70 side of the beacon, the transmitter may be so 75

operated as to transmit a dash on both sides of the beacon as a signal to indicate to the pilot the time of release of the pinion for reengagement with the driven gear. The signal in the code form is shown in Fig. 4. In the time interval 5 designated T_1 , the signal of both channels "A" and "N" is shown spaced in such manner that when the two lines are superimposed, which is the case when both signals are received simultaneously, a continuous tone modulation results. The time interval T_2 represents no code transmission. At the beginning of code transmission after the silent period T_2 , both channels start with a synchronizing signal shown by the dash 10 appearing in both the "A" and "N" lines. This signals the pilot to release the driving pinion 19 formerly described. After the synchronizing signal, the code appears again in the same sequence 15 as shown in T_1 .

20 To relieve the pilot of the necessity of manually synchronizing the apparatus as previously described, there is provided an automatic synchronizing circuit as disclosed in Fig. 5.

This apparatus consists of a vacuum tube device 25 comprising a triode or any suitable tube 22 coupled to the output of the receiver schematically indicated, which feeds the code signals to the input circuit of the tube 22 which includes the grid 23 and a voltage source indicated by the battery 39. The latter is of such magnitude as to bias the grid 23 to cut-off point or therebeyond, having its positive terminal connected to the cathode 31. The output circuit between the cathode 31 and the anode 26, includes the anode 35 voltage supply indicated by the battery 30 and the magnetizing coil of a relay 25. The latter is of the slow-to-release type, its armature making a conductive connection alternately between two sets of contacts 26 and 26' and 27 and 27', respectively, depending upon the position of the armature of the relay 25. The bridging of contacts 27 and 27' by the armature of the relay 25 completes a circuit through the battery 28 to the magnetizing winding of a second relay 29, also 40 of the slow-to-release type. This relay actuates a pair of contacts 32 and 32'. The former is connected to the contact 26' of the relay 25 and the latter to one terminal of the magnetizing winding of another relay 33. The other terminal 45 of this winding connects to the contact 34' actuated by the armature 35 of the relay 33. The corresponding contact 34 terminates at the common current source of both relays 29 and 33, namely, the battery 28. The contacts 34 and 34' 50 are normally closed and are opened upon excitation of the relay 33 which in turn opens the circuit and causes self deenergization. The action thereof will be described when considering the operation of the automatic synchronizing system. The armature 35 of the relay 33 is physically 55 so coordinated as to act upon the spring 37 of a clock mechanism 36, whereby this mechanism is wound up to furnish mechanical motive power during the time intervals of signal transmission, namely, the T_1 periods shown in Fig. 4. The clock mechanism 36 is intended to replace the driving motor 12 shown in Fig. 1. In other words the clock mechanism 36 is intended to drive the distribution cam 6 of Fig. 1.

70 Clock mechanisms of this type are well known, for example, in the so-called electric clocks in motor cars. These are mechanical clock movements and are periodically and automatically wound up by an electromagnet. In other words, 75 the spring 37 of the clock mechanism, when

pulled by the plunger 35 of the relay 33, is merely winding up the clock mechanism to thereby store up in the spring sufficient energy to drive an associated gear train, not shown in the schematic illustration, for such length of time as it takes 5 to send the marking signals "A" and "N". In signal beacons, the duration of time of the marking signals T_1 of Fig. 4 and the duration of time for the station identification signals T_2 in Fig. 4 which follows each marking signal period, is 10 maintained constant all the time. Therefore, the clock mechanism is set to run only for such duration of time as it takes to send the marking signal. At the end of this time it stops, 15 whereby the cam 6 connected to the clock mechanism will stop also. During the station identification period T_2 when no beam signals are sent, the clock mechanism remains deenergized and is wound up again when the first signal impulse following T_2 is received. This will be more fully 20 explained in the following description of the operation of the circuit.

In the operation of the circuit thus far described, and during the periods of no-signal reception, T_2 in Fig. 4, the armature of the first slow-to-release relay 25 will be deenergized and contact the lower contacts 27 and 27' thus maintaining the circuit through the second slow-to-release relay 29 in closed condition. Consequently, the armature of this second relay will occupy 25 its "in" position and will bridge the contacts 32 and 32', thereby setting up a circuit from 26' through 32 and 32', solenoid 33 and contacts 34' and 34 to battery 28. Now when the first signal impulse following T_2 is received, it overcomes the 30 blocking bias of battery 39 on grid 23, allowing current from battery 30 to energize relay 25. When the latter closes contacts 26 and 26', the solenoid 33 becomes energized, thereby winding the spring 37. As stated before, spring 37, when 35 wound, will drive cam 6 of Fig. 1 just so many revolutions corresponding to the period between T_2 periods which are regular and unchanging in number at all times. After the T_2 period, relay 25 remains energized until the next T_2 period and 40 likewise the relay 29 remains deenergized. Therefore, as a result, the first impulse excites the solenoid and draws in its plunger and winds up the spring. The movement of the plunger, however, breaks the circuit to the solenoid at the normally closed contacts 34 and 34' to permit the plunger to return to its initial position. By this 45 time, the circuit to the solenoid 33 will have been broken at the contact associated with the second relay 29.

It is to be noted in the operation of this circuit that the first impulse transmitted after the station announcement period results in a sudden winding of the spring followed by its return to its normal condition.

This sudden winding and release of the spring occurs only on the first impulse and not thereafter during the period of transmission of code signals since the first relay remains energized throughout the signalling period due first of all 50 to the fact that the signals are of interlocking character and the tone modulation will, therefore, remain practically continuous, and secondly, due to the fact that this relay is of the slow-to-release type and should any breaks occur in the signal for a short duration, the relay will carry over through these periods.

The action of the spring 37 is utilized as stated before in supplying energy to a clock motor or other driving means sufficient to drive the de- 55

ting cam 6 and continue the rotation thereof by throughout a period of code signal transmission.

The tone modulation referred to previously is the order of 1000 cycles per second. To prevent atmospheric disturbances from interfering in the operation of the first relay during the time when station announcements are being made, there is inserted a filter between the output of the receiver and the amplifier to be connected thereto, this filter being designed to pass energy at the tone frequency and to exclude energy at other frequencies, thus assuring operation of the first relay in response to the tone modulations only.

In the initial adjustment of the indicator, the coding cam 6 is so positioned on the shaft of the driven gear that the effect on one or the other of the ionizable gas columns will correspond to and be in synchronism with a portion of the signal which is transmitted after the first initial starting impulse, which, as explained above, may be the dash corresponding to the letter "T". When so adjusted, the apparatus is and ready for operation.

Referring to the operation of the indicator, when no automatic synchronizing means as shown in Fig. 5 are employed the cam driving motor 12 is brought up to proper speed, and its speed is held constant by the tone modulations being fed to the synchronizing winding 15 through the tuned circuit 16 and 17 in series with this winding. At the same time impulses corresponding to the code signals are fed from the output of the receiver to the neon indicating tubes in the way of the decoding switch, the action of which is under the control of the decoding cam. When the apparatus is properly adjusted, and assuming the letter "A" is to be indicated on the left-hand neon tube, the decoding cam will operate to close the circuit to the "A" tube through the decoding switch during such time periods as the dash and the dot of the signal "A" are being received by the receiver; and conversely the decoding cam will close the circuit to the "N" tube during such time periods as the dot and the dash of the signal "N" are being received by the receiver. With the motor held at the proper speed, the reproduction of the code signals at the proper rate and in their respective tubes will continue long as there is a continuous broadcasting of code signals without interruption either at the transmitter due to station announcements, or due to interruption by the pilot should he desire to listen in on his receiver to announcements or broadcasts on a different wave length. Once the apparatus gets out of synchronism due to any of the above reasons, the pilot merely releases the pinion from its normal position so that it will mesh with the cutout portion of the driven gear and halt rotation of the same with the decoding cam in a predetermined position. In knowing that the apparatus will again be in synchronism if started up on the dash of the letter "T", he may start the apparatus up again merely releasing the pinion and permitting it to return to its normal position in engagement with the driven gear at the moment that he hears the dash of the letter "T" in his earphones. The single dash of the letter T is sent simul-

taneously by both signal beams and is for the purpose of providing an impulse for marking the proper time when the rotation of the cam 6 may be started either by the pilot or automatically as previously described. If the interruption to the operation of the indicator is due to a station announcement, the pilot will merely listen for the first impulse after the station announcement, this impulse, of course, corresponding to the dash of the letter "T".

Where the automatic synchronizing feature is embodied in the indicator, the pilot is relieved of the burden of placing the apparatus in synchronism, as this result will automatically be obtained after each interruption due to station announcement, etc.

While the invention has been disclosed in great detail, various changes and modifications may suggest themselves to those skilled in the art, and it is not intended to be limited to the specific embodiment described except as may be necessitated by the prior art and the appended claims.

I claim as my invention:

1. A visual indicator for the reception of a pair of intersecting radio beams having identical carrier frequency, each being identified by modulation of dot and dash characters, said modulation being periodically interrupted by signals of a different character, comprising a pair of gaseous columns each representing one of said beams and each adapted upon energization to become luminous to a height depending upon the intensity and modulation character of said beams respectively, and means for establishing a uniform order of sequence between luminous excitation of said columns with respect to said beams after each said periodic interruption.

2. In a system for visually interpreting aural signals transmitted over a carrier wave modulated in sequence alternately by two sets of predetermined code characters, means for impressing said characters in sequential order discriminatingly as to said sets upon an indicating device, said means including a rotatable cam coupled to a driving motor by means of a gear train, said cam having peripheral configurations, switching means actuated by said cam for alternately energizing said device, the speed of rotation and the peripheral configuration of said cam cooperating with said switching means in such manner as to segregate said sets of characters into groups of like signals whereby said indicating device becomes discriminatingly energized in sequence by like sets of said code characters.

3. In a radio beacon system of the type where in a guiding beacon is established by the transmission of a pair of radio beams at an angle to each other, said beams being of identical carrier frequency and differentiated by successive transmission of modulation characters interlocking to form an uninterrupted tone modulation, visual means for indicating the reception of said beams comprising a pair of ionizable gas columns each representing one of said beams, and means for causing uniform ionization of both of said columns in accordance with said tone modulation and for causing differential ionization of said columns in accordance with modulation characters of either of said beams.
